United States Patent Office

Des. 184,321
Patented Jan. 27, 1959

184,321

TABLE LIGHTER OR SIMILAR ARTICLE

Alfred William Skinner, Epsom, England, assignor to
Ronson Corporation, Newark, N. J., a corporation of
New Jersey

Application April 1, 1958, Serial No. 50,275

Claims priority, application Great Britain
January 14, 1958

Term of patent 14 years

(Cl. D48—27)

Fig. 1.

Fig. 2.

Fig. 3.

Fig. 4.

Fig. 5.

Fig. 6.

Fig. 1 is a perspective view of a table lighter embodying my new design.

Fig. 2 is a side elevational view thereof;

Fig. 3 is a view in elevation thereof taken from the left of Fig. 2;

Fig. 4 is a top plan view thereof;

Fig. 5 is a view in elevation thereof taken from the right of Fig. 2; and

Fig. 6 is a bottom plan view thereof.

The characteristic features of my design for the table lighter disclosed, reside in the top portions above and blending in with the upper ornamental band, and having the configurations shown.

I claim:

The ornamental design for a table lighter or similar article, substantially as shown and described.
